AUTOMATIC FOOD BROILER

Samuel J. Temperato, 4 Ladue Manor, Ladue, Mo.

Filed Oct. 7, 1963, Ser. No. 76,892

Term of patent 14 years

(Cl. D81—10)

FIG. 1

FIG. 2

FIG. 1 is a front perspective view of an automatic food broiler showing my new design with the turn-over fork in its lowered position; and

FIG. 2 is a rear perspective view thereof with the turn-over fork in its raised position.

I claim:

The ornamental design for an automatic food broiler, substantially as shown and described.
